UNITED STATES PATENT OFFICE.

DELMER W. CALL, OF CLEVELAND, OHIO, ASSIGNOR TO THE NATIONAL
MALLEABLE CASTINGS COMPANY, OF SAME PLACE.

DESIGN FOR A HUB-BAND.

SPECIFICATION forming part of Design No. 35,036, dated September 3, 1901.

Application filed May 25, 1901. Serial No. 61,974. Term of patent 14 years.

To all whom it may concern:

Be it known that I, DELMER W. CALL, of Cleveland, in the county of Cuyahoga and State of Ohio, have invented a new and original Design for Hub-Bands, of which the following is a full, clear, and exact description, reference being had to the accompanying drawing, forming part of this specification, in which the figure shows in perspective view a hub-band embodying my design.

The leading feature of my design consists in a hub-band having a tapering portion and in addition thereto a figured portion extending around its circumference and constituted by a series of parallel plane surfaces which in cross-section constitute a polygon having a large number of sides.

In the drawing I show the hub-band, whose periphery is formed with a tapering portion 2, and at the outer end of the portion 2 a figured portion 3, constituted of a series of parallel plane surfaces which are longitudinal of the hub-band and extend around the periphery thereof.

I claim—
The design for a hub-band, substantially as herein shown and described.

In testimony whereof I have hereunto set my hand.

DELMER W. CALL.
